FULL ROD CARRIER

Lawrence L. McDonald, Park Ridge, Ill., assignor,
by mesne assignments, to Allen M. Rossman,
Wilmette, Ill.

Application July 29, 1940, Serial No. 348,197

10 Claims.

(Cl. 74—522.5)

This invention relates to apparatus adapted to act as a support for reciprocable power transmission lines and is more particularly concerned with straight line pull rod carriers.

The preferred embodiment of the present invention comprises a base mounted on two posts and to which a straight line motion mechanism is fastened at such points that the posts are in the line of motion of a carrier block carried by the straight line motion mechanism and slightly beyond the limits of the stroke of the carrier block. These posts serve the dual purpose of holding the carrier firmly in position and of acting as stop members to prevent the carrier block from swinging beyond the limit of substantially straight line motion. Friction loss in the pull rod line is less with the double post support than it is with the single post support.

It is an object of this invention to provide an improved, straight line motion pull rod carrier.

A further object of this invention is to provide a pull rod carrier of simplified, durable and economical construction.

Other objects of the invention will become apparent from the following description taken in conjunction with the accompanying drawings, of which:

Figure 1 is a diagrammatical, vertical front view of a carrier constructed in accordance with the invention; Figure 2 is a plan view of the apparatus, shown in Figure 1;

Figure 3 is a diagrammatical, vertical end view of the device shown in Figure 1;

Figure 4 is a diagrammatical, vertical view of a pull rod supported by a plurality of carriers constructed in accordance with the invention; and

Figure 5 is a plan view of the apparatus shown in Figure 4.

Referring to the drawings, numeral 1 indicates generally a pull rod carrier constructed in accordance with the invention. Numerals 2 and 3 indicate cylindrical or other shaped wooden posts or preferably hollow iron pipe driven or otherwise anchored vertically in the ground. A pair of elongated wooden beams 5 are bolted onto the pipes or posts 2 and 3 a short distance above the ground by means of elongated bolts 7 and nuts 9. As plainly seen from Figure 2, the bolts are inserted through horizontal holes drilled or bored through the beams 5 and the nuts are tightly drawn against washers 10 so that the beams 5 will be held securely on posts 2 and 3. As is shown in Figures 2 and 3, the beams 5 are secured together on pipes or posts 3 by means

of four bolts, the bolts preferably being placed adjacent to either side of the pipes or posts. The beams 5 are properly spaced from the top of the pipes 2 and 3 by means of steel hooks 6 having ends 6' and 6'' bent in reverse directions. The end 6'' is adapted to hook under the outside bolt 9 and the end 6' is adapted to hook over the upper end of the pipe 2 or 3. In addition to properly positioning the beams 5, hooks 6 prevent the beams from slipping downward on the posts and throwing the carrier out of line. In the device shown and described herein, the hooks are 6 inches long.

The arms 11 are pivotally supported in holes 13 and 15, bored horizontally through the beams 5. Holes 13 are the same distance from pipe 2 as the holes 15 are from the pipe 3. The arms 11 are retained in place in the holes 13 and 15 by means of washers 17 and spring clamps 19.

The upward extending rods 21 are integral with the horizontal arms 11 and have horizontal arms 23 integral therewith on the upper ends thereof. The rods 21 with the arms 11 and 23 are formed out of steel rods which are bent at the points 25 and 27 into the desired shape. For purposes of economics, junk $\frac{3}{4}$ " sucker rods used in oil well pumping operations may be bent into the required shape to form the arm 11, rod 21 and arm 23. As is apparent from Figures 2 and 3, rods 21 form with the arm 11 at an angle of slightly less than 90° and the rod 21 forms with the arm 23 at an angle slightly greater than 90°. Arms 11 and 23 extend in the same direction and are parallel to each other. As shown in Figure 2, the two arms 11 are inserted in the holes in beams 5 from opposite directions. By bending the rods in the manner just described, the arms 23 can be made shorter than arms 11 and the mid-portion of the arms 23 will lie directly over the space between the beams 5.

Wooden blocks 29 are pivotally mounted on the arms 23 by inserting the arms through horizontal holes bored through the lower portion of the blocks. The blocks are retained in place on the arms by means of washers which are spot welded to the rod 21. The blocks 29 are held in spaced relation by means of the horizontal tie rod 31 which is inserted through horizontal holes bored through the upper portion of the blocks 29 in a direction perpendicular to that of the holes through which the arms 23 are inserted. At a point 33 exactly midway between the points 35 and 37 at which the arms 23 are pivoted in blocks 29, a rod 39 is rigidly suspended from the tie rod 31. The rod 39 may be welded or other-

wise joined to the rod 31. As is apparent from Figure 3, rod 39 is not suspended vertically from the rod 31 but at somewhat of an angle. The lower portion of the rod 39 is bent to form a horizontal arm 41 on which is pivotally mounted a supporting block 43 by inserting the arm through a horizontal hole bored in the block. The block 43 is retained in place by means of suitable washers and spring clamps in the manner described in connection with the arms 11. The angle at which the rod 39 is suspended from rod 31 is such that the mid-section of the arm 41 overlies the space between the beams 5. The upper face of block 43 has a shallow wedged shape channel 45 cut therein in order to form a recess in which pull rod 47 is adapted to lie. The pipes 2 and 3, blocks 29 and block 43 all lie in the same vertical plane.

As is quite apparent from the drawings, the distance between the upper ends of the rods 21 is shorter than the distance between the lower ends, so that when the rod 39 is in a position exactly midway between the arms 21, as shown in Figure 1, the arms 21 both incline inwardly at the top toward the rod 39. Blocks and beams are all oil-soaked and the holes therein greased so that the holes therein will act as bearing surfaces for the arms which are adapted to oscillate in the holes. By oil soaking and greasing the blocks, the holes will furnish excellent bearing surfaces for an indefinite period without renewing the oil or grease.

The block 43 is adapted to reciprocate or oscillate along a substantially straight line over a limited stroke. The block does digress slightly from a straight line, but this digression will not be more than $\frac{1}{4}$ " either upward or downward if the device is properly proportioned. To obtain substantially straight line motion, a definite ratio must be maintained between the distance from the points 35 to 37 between the points 49 and 51, between the points 35 to 49 and 37 to 51, and the vertical distance from points 35 or 37 to point 53.

For example, where it is desired to use the carrier in connection with a pull rod for pumping oil wells from a central power, which rods are adapted to operate on a 40-inch stroke, the following dimensions are found to give substantially straight line motion:

	Inches
Distance from pipe 2 to 31	48 $\frac{1}{2}$
Distance from points 49 to 51	33
Distance from points 35 to 37	16 $\frac{1}{2}$
Distance from points 35 to 49 and from points 37 to 51	31
Vertical distance from point 35 or 37 to horizontal line drawn through point 53	25 $\frac{1}{4}$
Length of supporting block 43	4 $\frac{1}{2}$

The pipes 2 and 3 are 2 inches beyond the limit of travel of the block when the line is properly centered on the block. However, if the line is not properly centered so that the block 43 reciprocates in either direction beyond its limit of substantially straight line motion, it abuts against the posts 2 or 3, causing the motion of the carrier to stop, and permitting the pull rod 47 to slide in the channel or groove 45 until it is properly centered. When properly centered so that the block 43 ends its motion in either direction before contacting the posts 3, the rod will not slide on the block because of the weight of the rod and the friction between the block and the rod. While freely supporting the rod on the block as shown, breakage of the rods causing the rod to fly upwardly will not injure the carrier.

- In Figures 4 and 5 there is shown a pull rod 41 connected at one end to an eccentric 55 which forms a central source of power for a number of radially extending pull rods. The eccentric 5 is caused to oscillate by a suitable source of power and thereby reciprocates the pull rod which is connected at 51 to a pumping jack 59. The rod is supported at spaced intervals which may vary from approximately 15 to 40 feet by carriers 1. 10 The distance above the ground at which the rod is supported will be determined by the height of the eccentric and of the pumping jack connection above the ground and to some extent by the nature of the terrain.
- 15 By constructing the carrier in the manner shown and described, the carrier is firmly anchored to the ground so that it has no tendency to swing and the stresses are evenly balanced by placing the rods 21 on opposite sides of the beams 20 5. Moreover, the anchoring posts, by being properly spaced, serve as the stop members for the supporting block 43, thereby eliminating the necessity of providing stop arms on the lower tie rods.
- 25 It will be apparent to those skilled in the art that the carriers can be constructed from materials other than those herein disclosed. The particular materials were selected because of their cheapness and availability.
- 30 It is claimed:
1. In a device of the character described, a base, a member supported by said base in such manner that a point on said member moves along a substantially straight line when said member is oscillated, stops for limiting the movement of said point, said stops comprising a pair of supporting members for said base, the upper ends of which supporting members project into the path of said point at points slightly beyond the limits of the substantially straight line movement of said point.
2. In a device of the character described, a pair of upright supports, a base fastened to said supports, a pair of arms pivotally mounted in said base, a member pivotally suspended from said arms in such manner that a point on said member moves along a substantially straight line when said member is oscillated said upright supports being positioned at such points and extending upwardly such a distance as to permit reciprocation of said point within the limits of its substantially straight line motion but to prevent reciprocation beyond such limits.
3. A pull rod carrier comprising a pair of upright supporting posts, a horizontal base fastened to said posts, a pair of arms pivotally mounted on said base, a supporting member pivotally suspended between said arms in such manner that a point on said member moves along a substantially straight line connecting the upper portion of said posts when said member is oscillated, said posts being positioned with relation to said point so as to permit reciprocation thereof within the limits of substantially straight line motion but to prohibit reciprocation beyond such limits.
4. A device in accordance with claim 2 in which the arms are mounted on opposite sides of said base.
5. A carrier in accordance with claim 3 in which the arms are mounted on opposite sides of the base.
6. A pull rod carrier comprising a pair of spaced upright posts, a horizontal base fastened to said posts, a pair of upstanding arms pivotally

mounted in said base, said arms being mounted on opposite sides of said base, a supporting member pivotally suspended from said arms in such manner that a point on said member moves along a substantially straight line.

7. A pull rod carrier comprising a pair of spaced upright posts, a pair of horizontal beams, one on either side of said posts, supported on said posts, a pair of spaced apart upstanding arms having horizontal projections at their lower ends which are pivotally mounted in said beams, said arms being mounted from opposite sides of said beams, a horizontal projection on the upper end of each of said arms portions of which lie in the same vertical plane as said posts, and a reciprocable supporting member pivotally suspended from said upper horizontal projections in such manner that a point on said member moves along a substantially straight line when said member is oscillated.

8. A pull rod carrier comprising a pair of spaced upright supports, a horizontal beam on either side of said supports bolted together below the tops of said supports with bolts adjacent said supports, a hook of predetermined length, hooked at one end to the top of each of said supports and hooked at the other end to an adjacent bolt, a supporting member, means pivotally mounting said member on said beams in such manner that a point on said member moves along a substan-

tially straight line when said member is oscillated, said supports being positioned at such points and extending upwardly such a distance as to permit reciprocation of said first mentioned point within the limits of its substantially straight line motion but to prevent reciprocation beyond such limits.

9. A pull rod carrier including a base comprising two spaced side by side parallel beams, a straight line operating linkage pivoted on said beams, said linkage having means for supporting a horizontally reciprocating pull rod and guiding it in a straight line motion, a pair of spaced upright supporting posts straddled by said beams, and means securing the beams to the posts.

10. A pull rod carrier including a base comprising two spaced side by side parallel beams, a straight line operating linkage pivoted on said beams, said linkage having means for supporting a horizontally reciprocating pull rod and guiding it in a straight line motion while permitting sliding of the pull rod with respect to the supporting means, a pair of spaced upright supporting posts straddled by said beams, means for securing the beams to the posts, said posts extending into the path of motion of a part of the structure connected with the linkage and constituting two limiting stops for limiting the travel of the linkage.
